UNITED STATES PATENT OFFICE.

NELSON J. SANFORD, OF MELROSE, MASSACHUSETTS.

PLASTERER'S TOOL.

1,294,543.

Specification of Letters Patent. Patented Feb. 18, 1919.

Application filed July 23, 1918. Serial No. 246,371.

To all whom it may concern:

Be it known that I, NELSON J. SANFORD, a citizen of the United States, residing at Melrose, in the county of Middlesex and 5 State of Massachusetts, have invented new and useful Improvements in Plasterers' Tools, of which the following is a specification.

This invention relates to a plasterer's tool 10 known as a plasterer's bevel edge. The plasterer's bevel edge as at present used is made of wood beveled along one edge and the use of the tool is to finish the plastered walls and the ceiling of a room, especially 15 in the corners of the room. Plasterer's bevel edges made of wood are objectionable on account of the expense and of the fact that they will warp when wet and that the edge becomes dulled, chipped or otherwise 20 damaged in use.

The object of this invention is to provide a plasterer's bevel edge tool which will be strong, light and durable and the edge of which will give prolonged service, perform 25 accurate work and which may be removed and a new blade or scraper substituted therefor with very little expense or trouble.

To these ends the invention consists in a 30 plasterer's tool such as hereinafter described in the specification and particularly pointed out in the claims.

Referring to the drawings:

Figure 1 is a plan view of a plasterer's bevel edge tool constructed in accordance 35 with my invention.

Fig. 2 is a cross section taken on line 2—2 of Fig. 1.

Fig. 3 is a cross section of a modified form of my invention.

40 Like numerals refer to like parts throughout the several views of the drawings.

In the drawings, referring to Figs. 1 and 2, 5 is a strip of sheet metal constituting a scraper, preferably beveled at 6 along its 45 edge. 7 is a holder consisting of a piece of sheet metal bent to form oppositely disposed converging sides 8 and 9. Along one edge of said holder the sheet metal is turned inwardly to form a channel-shaped member 10 and the scraper 5 projects into the slot 11 in said channel shaped member and is preferably fastened to the holder by means of the rivets 12.

A handle 13, preferably of wood, ex- 55 tends along the edge of said holder opposite the channel-shaped edge and between

the two sides 8 and 9 of said holder the handle 13 is fastened by rivets 14.

The blade 5 is preferably beveled along its opposite edges and can be reversed when 60 it becomes worn so as to utilize both of the edges.

In Fig. 3 a modified form of my invention is illustrated which is entirely of metal and consists of a scraper blade 15 which is 65 made of comparatively thin metal so that it need not have its edges beveled. This scraper blade projects into a slot 16 in a channel-shaped member 17 formed along the edges of the converging sides 18 and 19 70 of a holder 20. Said holder is extended laterally from the diverging edges of the sides 18 and 19 to form parallel sides 21 and 22 and a rear edge 23, forming, as a whole, a hollow handle 24, and the metal 75 forming the rear edge 23 being bent to form a flange 25 which is fastened by rivets 26 to the side 22.

A channel-shaped piece 27 extends along the tool between the sides 21 and 22 and 80 is riveted thereto for the purpose of stiffening and strengthening the holder and handle portions of the tool.

The tool is used in the same manner as the ordinary plasterer's bevel edge tool and 85 in a manner well known to those skilled in this art.

Having thus described my invention, what I claim and desire by Letters Patent 90 to secure is:

1. A plasterer's tool having, in combination, a strip of sheet metal constituting a scraper and a sheet metal holder therefor having two oppositely disposed sides converging laterally toward each other and 95 a channel-shaped portion integral therewith, having parallel sides forming a slot adapted to receive and hold said scraper.

2. A plasterer's tool having, in combination, a strip of sheet metal constituting a 100 scraper, a sheet metal holder therefor comprising two oppositely disposed sides converging laterally toward each other, a channel-shaped portion having parallel sides forming a slot extending longitudinally 105 along one edge of said holder and adapted to receive and hold said scraper and a handle extending along the opposite edge of said holder between said sides and fastened thereto.

3. A plasterer's tool having, in combination, a strip of sheet metal constituting a 110

scraper, a sheet metal holder therefor substantially V-shaped in cross section, a channel-shaped member inclosed between the opposite sides of said V-shaped holder and extending along one edge thereof, a slot in said channel-shaped member adapted to receive and hold said scraper, and a handle extending along the opposite edge of said holder projecting between the opposite

sides of said V-shaped holder and fastened thereto.

In testimony whereof I have hereunto set my hand in presence of two subscribing witnesses.

NELSON J. SANFORD.
